Patented Oct. 23, 1923.

UNITED STATES PATENT OFFICE.

FREDERICK W. MARHEINE, OF SPOKANE, WASHINGTON.

CONVERTIBLE CHAIR.

Application filed January 20, 1923. Serial No. 614,033.

To all whom it may concern:

Be it known that I, FREDERICK W. MARHEINE, a citizen of the United States, residing at Spokane, in Spokane County and State of Washington, have invented certain new and useful Improvements in Convertible Chairs, of which the following is a specification.

My present invention relates to an invention 10 proved convertible chair involving a special construction whereby the chair may readily and with facility be converted for use either as a rocking chair or a non-rocking chair. The primary object of my invention is the provision of means in connection with a non-rocking chair whereby the latter may have the required arms or braces at its sides and be adapted for use as a strong and rigid structure for ordinary use. And by facile 20 manipulation of adjustable parts, the arms or side braces of the non-rocking chair may be positioned for use as rockers for a rocking chair. Means are provided for rigidly locking the adjustable braces in position 25 when used either as side arms or as rockers. And such means, which are of simple and compact construction, only slightly modify the appearance of the convertible chair, thus providing an article of furniture that may 30 be utilized as a piece of a set of furniture, and which avoids the appearance of an extra or additional chair.

In the illustrated form of the invention the novelty thereof resides in certain combinations and arrangements of parts as will 35 hereinafter be fully described and claimed, and in the accompanying drawings one complete example of the physical embodiment 40 of my invention is depicted, wherein the parts are combined and arranged according to one mode for the practical application of the principles of my invention.

Figure 1 is a perspective view of the convertible chair adapted as a rocking chair. 45 Figure 2 is an enlarged view in elevation at the rear of the chair, showing it as a non-rocking chair, and with the locking latch in dotted lines to illustrate the manner of manipulating the latch.

50 Figure 3 is a view in side elevation of the convertible chair used as a non-rocking chair.

Figure 4 is an enlarged, fragmentary, perspective view illustrating the manner of 55 securing the side braces, as chair-arms for the non-rocking chair, to the chair.

As illustrated in the drawings the seat 1 is of usual or standard construction and supported on the two front legs 2, 2 and the two rear, longer legs 3, 3, the latter extending up above the seat 1 to form part of the chair back 4.

The usual horizontal braces 5, 5, are fixed in sockets in the four chair legs to provide a rigid and durable structure, and the structure as thus described forms a chair of well known and non-rocking type.

In connection with the chair structure I utilize side braces 6, 6, one at each side of the chair, and each of these braces is pivoted as at 7 at the outer side of and near the bottom of the front chair legs 2, 2. These side braces are preferably of the same material as the chair and conform to the design or style of the chair. At their rear, free ends the side braces are provided with enlargements, as 8, which in this instance are fashioned as a spiral curve projecting from the slightly curved brace 6, in such manner as to be positioned in front of the back posts or legs 3 of the chair and above the seat 1. In Figures 2 and 3 the side braces are illustrated as extending upwardly and rearwardly from their front pivots 7, with the curved portion or scroll 8 above the seat and forward of the rear posts or legs to perform the functions of side arms for the non-rocking chair.

For locking the side braces in position as side arms for the non-rocking chair I utilize a notch 9 in the upper face of each side brace, which notch is spaced from the pivot center 7 in position to embrace a laterally extending pin 10, one at each side of the chair. Preferably these pins are fixed 90 in the outer sides of the rear legs, just below the line of the seat 1, and they project laterally or outwardly from the chair as indicated to be seated in the complementary notch as indicated in Figure 4.

When utilized as a non-rocking chair, the side braces are locked in position by means of a pair of turn buttons 11, one pivoted on the rear face of each rear leg, back of and a little below the fixed pins 9. With the side braces turned up to position of Figure 3, it will be apparent that the turn buttons 11 may be turned to horizontal position of Figure 2 to prevent the side braces from falling or swinging down, and the braces are each held rigidly and securely between the respective pins and turn-buttons.

When the non-rocking chair is to be converted for use as a rocking chair, the side braces are released by turning the turn-buttons 11 to vertical position in Figure 2 to free the braces and permit them to be swung on their pivots 7, and the lower curved edges of the side braces are adapted to be projected slightly below the pairs of side legs 2-3 to afford rocking supports for the chair.

In this position the side braces are adapted to be engaged by a single latch bar 12, located at the rear of the chair near the bottom ends of the two rear legs 3, 3. At 15 one end, the latch bar is pivoted, as at 13 to one rear leg of the chair, to swing as indicated in dotted lines Figure 2, and near the free end of the latch bar the latter is provided with a transverse groove 14 in its 20 upper edge. This groove is adapted to contact with a fixed stud or headed pin 15 which projects rearwardly from the rear face of one of the rear legs, and the walls of the notch embrace the stud or pin 15 as shown. 25 Each end of the latch bar is fashioned with a corner notch to form a hook 16 adapted to engage over the upper edge of one of the rockers or braces 6, as best seen in Figure 1, and the pivoted latch bar is provided with a pivoted turn-button 17 carried on the upper edge of the latch bar and near its free end.

Thus it will be apparent that when the side braces are turned down to the position for use 35 as rockers in Figure 1 (while the latch bar is in dotted position Figure 2) they may readily and conveniently be locked in position by use of the latch bar. When the side braces have been adjusted to proper posi-

tion the latch bar is turned on its pivot so 40 that the two hooks 16 will project over the top edges of the respective rocker members. The load or weight of the chair imparted to the rocker members is taken up by the hooked ends of the latch bar, and then transferred to the rear legs of the chair through the pivot pin 13 and the stud 15. The turn button 17 is utilized to prevent sagging of the latch bar when the latter is not in engagement with the rocker members.

From the above description taken in connection with my drawings it will be apparent that the convertible chair may quickly and with facility be adjusted in either of the two described positions, and when so adjusted, the parts may be rigidly and securely locked to maintain the chair in condition for use.

Changes and alterations may be made in the described and illustrated structure, within the scope of my claim, without departing from the spirit of my invention, and such changes are contemplated.

Having thus fully described my invention, what I claim as new and desire to secure by Letters Patent is:—

The combination with the front and rear legs of a convertible chair, of a pair of side members adapted to form rockers and pivoted at the lower outer sides of the front 70 legs, a transverse latch bar pivoted at one end to a rear leg, end hooks on said bar to engage over said rockers, said latch bar having a transverse groove in its upper edge near its free end, and a stud in one of said 75 rear legs for co-action with said groove.

In testimony whereof I affix my signature.
FREDERICK W. MARHEINE.
